UNITED STATES PATENT OFFICE.

GOTTFRIED EICKHOFF AND PETER ERNST THEODOR JUHL, OF COPENHAGEN, DENMARK.

MACHINE FOR PRINTING CYLINDRICAL OBJECTS.

SPECIFICATION forming part of Letters Patent No. 624,771, dated May 9, 1899.

Application filed January 21, 1897. Serial No. 620,086. (No model.)

To all whom it may concern:

Be it known that we, GOTTFRIED EICKHOFF and PETER ERNST THEODOR JUHL, citizens of the Kingdom of Denmark, residing at Copenhagen, Denmark, have invented certain new and useful Improvements in Machines for Printing Cylindrical Objects; and we do hereby declare the following to be a full, clear, and exact description of the invention, such as will enable others skilled in the art to which it appertains to make and use the same, reference being had to the accompanying drawings, and to letters and figures of reference marked thereon, which form a part of this specification.

Our invention has relation to printing-machines, and more particularly to machines for printing upon cylindrical or approximately cylindrical bodies, such as tin cans containing alimentary and other substances, any desired subject-matter or different subjects-matter in one and the same color or in different colors, or for applying to such cylindrical bodies one or more coats of varnish or the like.

The invention has for its object the provision of mechanism or mechanisms by means of which the cylindrical body which is to receive the impression or impressions is maintained during the operation of printing in proper position to receive such impression or impressions and is at the same time revolved with the printing-cylinders in one and the same direction and at the same surface speed.

The invention has for its further object an arrangement of cylinder or cylinders whereby a plurality of cylindrical bodies may be printed upon at one and the same time, means being also provided for feeding the cylindrical bodies to the printing appliances and discharging said bodies from the machine after having been printed upon.

That our invention may be fully understood, we will describe the same in detail, reference being had to the accompanying drawings, in which—

Figure 1 is a side elevation, Fig. 2 a sectional plan, (the upper printing-cylinder removed,) and Fig. 3 a sectional end view, (the lower left-hand printing-cylinder removed,) of a machine for printing upon cylindrical bodies. Fig. 4 is a sectional detail view illus-

trating rolling bearings adapted to be substituted for the upper printing-cylinder. Fig. 5 is a fragmentary sectional view of Fig. 1, illustrating the feed-bar in its uppermost position about to deposit a tin on the lower printing-cylinders and at the limit of its traversing motion toward the left; and Fig. 6 is a like view illustrating said feed-bar in its lowermost position and at the limit of its traversing motion toward the right, said figure also illustrating an arrangement of printing-cylinders whereby two tins may be printed upon simultaneously. Fig. 7 is an enlarged cross-section of the feed-bar, and Fig. 8 is an enlarged side view of one of the bearings for the upper printing-cylinder.

The main frame F is provided near one end (the right-hand end, Fig. 1) with bearings for a main shaft s, which carries two cams c and c' and a crank c², the pin of which is connected by a rod r with a toothed sector-lever S³, adapted to oscillate on a cross-brace f' of the frame F near its opposite or left end. A rock-lever L, fulcrumed about midway of its length to the frame F at f², carries at one end a roller l¹ in contact with and actuated by the cam c, above referred to.

From the frame F project standards or arms f, one on each side thereof, to which is secured a cross brace or shaft s', that carries a loose sleeve a, having a radial arm A, which carries at its free end a roller a⁵ in contact with and actuated by the aforementioned cam c'. The sleeve a also has two arms A', the forward or left end of which is bifurcated or branched. One of said branches a' is angular and its horizontal arm is enlarged and has formed therein a segmental slot a⁶, a bearing being provided at the angle of the horizontal and upwardly and forwardly inclined parts of the branches a' of said arms A' for a cross-shaft s². To the opposite ends of shaft s² are pivoted links L³, which by means of set bolts or screws l², working in the aforesaid segmental slots, are adjustable toward and from the main frame or lower printing-cylinders to adapt the machine to print upon tins of different diameter, the slots a⁶ being arcs of circles having the axis of shaft s² for center.

In the outer ends of the links L³ are formed bearings for the journals or shafts s of the

upper printing-cylinder C, and from the link L³ on the feed side of the machine projects a stud s³, that carries a sleeve i, adjustable lengthwise of, as well as about, the stud by means of a set-screw i², and in said sleeve is seated a pointer or index-finger I, adjustable vertically by means of a set-screw i', as more clearly shown in Fig. 8, for purposes presently explained.

- 10 The branch a² of arms A' extends forward and downward, terminating in a foot portion a⁵, to which is secured an arm a³, that has at its upper end an inwardly-projecting V-shaped lip a⁴, that projects into a longitudinal guide-groove b in the feed-bar B. The proximate faces of the arms a³ and the branch a² of arm A' converge to form a V-shaped recess or bearing for and in which said feed-bar has a traversing motion, as more clearly 15 shown in Fig. 7.

The frame F near its forward or left end is provided with bearings for the journals or shafts S' S² of the lower printing-cylinders C' and C², arranged on opposite sides of a line 20 intersecting the axis of rotation of the upper printing-cylinder C, and between said cylinders C' C² is located the feed-bar B, which not only has a traversing motion, as stated, but also a rising-and-falling motion, as hereinafter explained.

To one end of the shafts S' S² is secured a gear-wheel 7 and 8, respectively, both in gear with the toothed sector-lever S³, hereinbefore described, and on the opposite end of shaft 25 S' is secured a gear-wheel 6, that meshes with a transmitting-wheel 5 on branch a' of the arm A' on that side of the machine—i. e., the delivery side—said wheel 5 communicating motion to a like wheel 4, revolvable on a stud 40 on said branch a' of arm A', said wheel 4 communicating motion to a wheel 3, loose on shaft s², which wheel 3 communicates motion to a gear on the shaft S of the upper printing-cylinder.

45 Each of the printing-cylinders is provided with an inking-in roll (indicated by the common symbol 9) and which may be arranged in any preferred or usual manner.

The toothed sector-lever S³ and the driving 50 gearing described are so organized as to impart to the printing-cylinders a complete revolution at each oscillation of the said sector-lever and to revolve said cylinders at the same surface speed.

55 On the feed side of the machine, Fig. 1, is arranged a longitudinally and transversely slotted support D, the four upright members d thus formed having concave upper faces forming a saddle for the tins to be fed to the printing appliances, and between said four members the feed-bar B has motion, the construction of the support facilitating the placing thereon of the tins in proper position, in that the operator has access thereto from 60 practically all sides. The outer members of the support D are provided with an inwardly-

projecting flange d', that serves as an abutment for the tins, and on the delivery side of the machine, (left hand, Fig. 3,) is arranged an inclined delivery-table K, having flanged guideways k k', the latter being adjustable toward and from the former, so as to properly guide tins of different lengths along said table.

At the receiving end of the delivery-table 75 K is arranged a bracket H, to which is adjustably secured a stop h, which latter lies in the plane of the tins on the feed-bar B and acts as a knock-off to knock the tins after having been printed upon off the feed-bar onto 80 the delivery-table K.

On the delivery side of the machine the feed-bar B is connected by a link l³ with the vertical arm l' of a bell-crank lever L', the horizontal arm l² of which is weighted or carries a weight L². The outer end of said horizontal arm l² of lever L' is provided in its under face with a concave socket-bearing, a similar bearing being formed in the end of lever L, hereinabove referred to, in which 85 bearings is stepped a connecting-rod l⁵, thus providing a universal joint between the two levers L and L'.

In practice and to properly revolve the tins when the forms M on the printing-cylinders 95 cover but a portion of their circumference each of said cylinders has on its end toward the feed side of the machine a peripheral flange c², a ring c³, provided with a like flange and adjustable lengthwise of the cylinder, being provided to coöperate with said end flange and form bearings for the tins to properly position the same relatively to the forms M and at the same time cause them to revolve about their own axes with the printing-cylinders. 100

In some cases, especially when the body to be printed upon is not perfectly cylindrical, the bearing-flanges may be formed of rings c⁴, Figs. 3 and 5, of a more or less elastic material, as rubber, seated in grooves in the cylinders over the rings c³.

The feed-bar B, as above stated, is substantially V-shaped in cross-section—that is to say, it has converging sides—and is provided with a longitudinal groove b' for the retaining and guiding lip on the outer half of the bearings for said bar on the branches a² of arms A'. In its upperface the bar has a dovetailed groove in which are fitted bearing-blocks b², adjustable lengthwise of the bar 115 for supporting the tins T.

The operation of the machine is as follows: A tin T having been placed upon the support D, so as to abut against the end flanges of its outer uprights, is now properly positioned 120 for being printed upon by the aid of the index-finger I, hereinabove referred to, while the feed-bar is in its lowermost position and at the limit of its traversing motion toward the feed end of the machine. As the crank c² revolves the arms A' are lifted by the cam c', thereby moving the upper printing-cylin-

der C away from the lower cylinders C' C², while the feed-bar is likewise lifted by the branches a² of said arms A', this taking place when the crank c² is about to reach and while it passes a dead-point, consequently while the printing-cylinders C' C² are almost at rest. As the feed-bar B rises its bearings b⁶ are brought under the opposite ends of the tin T on support D and lift said tin off, end- wise motion of the tin on its bearings b² being prevented by the end flanges b³ thereon. At this moment the cam c acts upon the roller l⁴ on lever L, depressing its roller end and lifting its opposite end, thereby tilting the bell-crank lever L' toward the left, Fig. 3, whereby a traversing motion in the same direction is imparted to the feed-bar B, and the tin T thereon is carried between the cylinders C' C² and below cylinder C into position to be printed upon. The feed-bar B now descends, leaving the tin upon the bearings c² c³ on cylinders C' C², and simultaneously therewith the upper cylinder C likewise descends, with its corresponding bearings c² c³ moving into contact with the said tin. During these operations the cam c has rotated sufficiently to cause the feed-bar B, after having reached its lowermost position, to be traversed back toward the feed end of the machine under the weight L² of bell-crank lever L', ready to again rise and take a second tin from support D. During the described movements the cylinders C' C² revolve in the same direction as the main shaft s, the sector-lever S³ having now reached the limit of its motion toward the right. Fig. 1 is now moved toward the left to revolve the printing-cylinders C' C² C³ in a reverse direction, and through said cylinders the tin T between them is revolved and printed upon. During the last-described operation the feed-bar B is again raised, and as the sector-lever S³ reaches the limit of its movement toward the left the crank c² again passes a dead-point. The feed-bar takes a second tin T' from support D and is traversed toward the delivery end of the machine to carry said second tin T' into proper position between the printing-cylinders. As the feed-bar B rises to take said second tin from support D it also takes the tin previously printed upon off the lower printing-cylinders, and as said feed-bar is traversed toward the delivery side of the machine the tin T is carried into position to be printed upon and the tin T strikes the abutment or stop h on bracket-arm H, and is thereby knocked off onto the delivery-table K, down which it rolls, the described operation being then repeated, and so on.

In a machine such as described three independent impressions can be made upon each tin and of course in the same or in different colors. If, however, the subject-matter to be printed upon the tins is such as to require only one or two cylinders, the other cylinder or cylinders are removed and their shafts

provided with discoidal bearings E, adjustable lengthwise of said shafts by means of set-screws e, Fig. 4. On the other hand, the machine may readily be adapted to the printing upon two or more tins simultaneously, either by three or five cylinders, as shown in Fig. 6, in which the upper short cylinder C is replaced by a longer cylinder C^X, having two forms M, and instead of two lower cylinders we employ four, of which two only are shown in Fig. 6—namely, the cylinder C' and a companion cylinder C²¹ on the same shaft S'. Inasmuch as the cylinders are removably secured to their shafts in any well-known manner the changes referred to can be readily effected or discoidal bearings E substituted for one or more of the printing-cylinders, as will be readily understood.

When very small cylindrical bodies are to be printed upon, the bearings b² on the feed-bar B may be dispensed with.

As will readily be seen, the upper printing-cylinder C or C^X or the shaft S and its discoidal bearings E perform the function of pressure-rolls relatively to the tin revolved by and between them.

Having thus described our invention, what we claim as new therein, and desire to secure by Letters Patent, is—

1. A machine for printing upon cylindrical bodies comprising a printing surface or form moving alternately in opposite directions, two sets of bearings moving correspondingly to revolve a cylindrical body placed between said elements, and mechanism for periodically moving one of said elements from the others and back again to admit of the placing of a cylindrical body between them and its removal after being printed upon, for the purpose set forth.

2. A machine for printing upon cylindrical bodies, comprising a printing surface or form, moving alternately in opposite directions, two sets of bearings moving correspondingly to revolve a cylindrical body placed between said elements, mechanism for periodically moving one of said elements from the others and back again, a feeding device constructed to receive and support cylindrical bodies, and mechanism for imparting to said device the proper movements to carry a cylindrical body between the aforesaid elements and remove the body previously printed upon when one of said elements is moving away from the others, for the purpose set forth.

3. A machine for printing upon cylindrical bodies, comprising a printing-surface moving alternately in opposite directions two sets of bearings moving correspondingly to revolve a cylindrical body when placed between said elements, and mechanism for periodically moving one of the elements toward and from the others; in combination with a feed-bar constructed to support cylindrical bodies, and mechanism organized to impart to said feed-bar alternating horizontal and vertical recip-

roating movements between two of the aforesaid elements, the horizontal and vertical movements of the bar in one direction being timed to take place when one of the aforesaid 5 elements is moving from the others, for the purpose set forth.

4. A machine for printing upon cylindrical bodies, comprising a printing surface or form moving alternately in opposite directions, one 10 or more similar surfaces moving correspondingly to revolve a cylindrical body when placed between them, and mechanism for periodically moving one of said printing-surfaces from the other or others and back again 15 to admit of the placing of a cylindrical body between them and its removal after being printed upon, for the purpose set forth.

5. A machine for printing upon cylindrical bodies, comprising a printing-surface or set 20 of such moving alternately in opposite directions, a second printing-surface or set of such moving correspondingly to revolve a cylindrical body or bodies when placed between them, and mechanism for periodically moving 25 one of the printing-surfaces or a set of such from the other or others and back again; in combination with a feeding device for feeding cylindrical bodies between the printing-surfaces when one or a set of them is moved 30 from the other, for the purpose set forth.

6. In a machine for printing upon cylindrical bodies, the combination with a revolute printing-cylinder provided with a circular bearing on each side of its form, and two or 35 more sets of like revolute bearings coöperating with those on the cylinder to revolve a cylindrical body in a position to be acted upon by said form, and mechanism adapted to automatically and periodically move one or more 40 of the aforesaid sets of circular bearings toward or from the printing-cylinder, for the purpose set forth.

7. In a machine for printing upon cylindrical bodies, the combination with a revolute printing-cylinder provided with a circular bearing on each side of its form, two or more sets of like revolute bearings coöperating 45 with those on the cylinder to revolve a cylindrical body in a position to be acted upon by said form, and mechanism adapted to automatically and periodically move one or more 50 of the aforesaid sets of circular bearings toward and from the printing-cylinder; of a feeding device operating automatically to feed a cylindrical body to the printing appliances whenever one or more of the sets of circular 55 bearings have moved from the printing-cylinder, for the purpose set forth.

8. In a machine for printing upon cylindrical bodies, the combination with a plurality 60 of revolute printing-cylinders, each provided with a circular bearing on opposite sides of its form, and a set of revolute circular bearings coöperating with those on the printing-cylinders to revolve a cylindrical body in position to be acted upon by the forms on said 65

cylinders; of mechanism adapted to automatically and periodically move said set of circular bearings toward and from the printing-cylinders, for the purpose set forth. 70

9. In a machine for printing upon cylindrical bodies, the combination with a plurality of revolute printing-cylinders, each provided with a circular bearing on opposite sides of its form, a set of revolute circular bearings 75 coöperating with the like bearings on the printing-cylinders to revolve a cylindrical body in position to be acted upon by the forms on said cylinders, and mechanism adapted to automatically and periodically move said set of circular bearings toward and from the printing-cylinders; of a feeding device operating automatically to feed a cylindrical body to the printing appliances whenever said set of circular bearings has moved away from the cylinders, for the purpose set forth. 80 85

10. The combination with the printing-cylinders C' and C'', a feed-bar located between them, the shaft S, and mechanism adapted to periodically and simultaneously lift the said 90 feed-bar and shaft; of mechanism organized to impart to the feed-bar a traversing motion in one direction when so lifted, and a like motion in a reverse direction when again lowered, for the purpose set forth. 95

11. The combination of the lifter-arms A' having a branch a², a guide and retaining-arm secured to said branch and provided at its upper end with an inwardly-projecting lip, the proximate faces of said retaining-arm and 100 branch of lifter-arm converging to form between them a bearing V-shaped in cross-section, with the feed-bar B having converging sides to fit said bearing, and a longitudinal groove for the reception of the lip on the retaining-arm, for the purpose set forth. 105

12. In a machine such as described, a feed-bar having converging sides, a longitudinal groove in one of said sides and a like dovetailed groove in its upper face; in combination with bearing-blocks fitting said dovetailed grooves, and having concave bearing-faces terminating in upwardly-projecting end flanges, for the purpose set forth. 110

13. In a machine such as described, the 115 combination with the feed-bar B, the shaft s and the cam c thereon and the lever L actuated by said cam; of the weighted bell-crank lever L' and connections connecting the vertical and horizontal arms thereof respectively 120 with one end of the feed-bar and with one end of said lever L, for the purpose set forth.

14. The combination with the feed-bar B and the bell-crank lever L' having its shorter arm weighted and its longer arm connected 125 with the feed-bar by a link l³; of the lever L, a universal-joint connection between one end of said lever and the weighted arm of bell-crank lever L', and means for periodically rocking said lever, for the purpose set forth. 130

15. The combination with the feed-bar B and the bell-crank lever L' having its shorter

arm weighted and its longer arm connected with the feed-bar by a link l^3 , said shorter arm having a concave bearing in its under face; of the lever L having a corresponding bearing at one end in its upper face, the connecting-rod l^5 loosely stepped in said bearings, and means for periodically rocking said lever L, for the purpose set forth.

In testimony that we claim the foregoing as our invention we have signed our names in presence of two subscribing witnesses.
